CAST RAIL CROSSING STRUCTURE

Charles H. Nordberg, Chicago Heights, Ill., assignor to Pettibone Mulliken Corporation, a corporation of Illinois

Application May 23, 1944, Serial No. 536,917

9 Claims. (Cl. 246—464)

1

This invention relates to an improved construction for railroad crossings and the like.

Cast crossings are of two types, the one type comprising a cast member or members of box-like or shell section and adapted to be bounded by rolled rail. The cast member is preferably of manganese alloy steel. This type of construction is known in the trade as rail-bound insert construction. In the other type, the entire crossing may be of cast manganese alloy steel, or the like, also of box-like or shell section. This type of construction is known as solid construction. The present invention is adapted for both such types.

These types of devices, heretofore, have been subject to a number of drawbacks which manufacturers have constantly attempted to overcome. For example, in crossings of box-like section, even where provided with certain types of interior reinforcing means, there is a tendency to produce shrinkage cavities in the metal. Moreover, the disposition of the strengthening means was such that fatigue cracking often resulted from repeated flexing of the casting under passing trains.

The present invention has for a principal object the provision of a structure for crossings and the like, which avoids the disadvantages to which reference has been made.

These and other objects of the invention will become more apparent from the following description, claims and accompanying drawings, in which:

Figure 1 is a top plan view of a crossing constructed in accordance with one form of the invention;

Figure 2 is a section taken on the line 2—2 of Figure 1;

Figure 3 is a top plan view of a crossing constructed in accordance with another form of the invention; and

Figure 4 is a section taken on the line 4—4 of Figure 3.

Figures 1 and 2 illustrate the application of some features of the invention of a manganese alloy steel railroad crossing element 34 which may be formed as an integrally cast box-like or shell-like structure. The arms of the structure are formed to receive the rails 36, 38 with portions 40, 42, respectively, of these rails. Rail guard members 44, 46 may be employed to insure that the flanges of the car wheels are properly directed to the flangeways 48, 50 formed in the upper surface of crossing element 34. The crossing element 34, rail guards and rails are adapted

2

to be supported on base plates 35 supported in turn by ties or the like (not shown).

While box-like crossing elements have been provided with interior strengthening means heretofore, an important feature of the present invention resides in the provision of improved strengthening means, particularly at the center of the crossing element 34. In addition to the arcuate, transverse ribs 52, 54, 56 and 58 such means are comprised of the single strengthening rib 60 which is bent at right angles at the exact center of the crossing element. These strengthening means are shown in dotted lines in Figure 1 and some of them are also shown in the section, Figure 2.

It will be noted that the strengthening rib 60 is disposed directly beneath the flangeways 48, 50 thus eliminating sagging effect by giving real support at the points of the crossing subjected to heaviest punishment. The webs 52, 54, 56 and 58 do not extend to the under surface of the top of the crossing (see Figure 2).

Additional strengthening webs may be provided for the arms of the crossing, such as for example, those indicated by the numerals 62, 64, in Figure 1.

The modification illustrated in Figures 3 and 4 is generally similar to that just described. Arcuate strengthening webs 66, 68, 70 and 72 are employed. The crossing element is formed with a strengthening rib 74 which is disposed directly beneath the flangeway 76 and extends from web 66 to web 70. Another strengthening rib 78 is disposed beneath the flangeway 80 and extends adjacent to but does not meet with the rib 74. The rib 78 connects at its other end to the web 68. A third web 28, also disposed beneath the flangeway 80, extends from the rib 72 to a point adjacent to, but not meeting with, the rib 74. This structure thus eliminates shrinkage cracks and at the same time enables the crossing to be light in structure with all the necessary strength provided at the points where strength is required.

It is apparent that the inventive features disclosed may be applied to cast crossing inserts adapted to be bound by bolts and the like to standard rail sections.

While various types of steel may be employed for the crossing structures described, manganese steel alloys have been found to be admirably suited to the purpose as the pounding such elements receive in usage only improves the toughness of the metal and, in fact, increases the period of usefulness of the devices.

55 While I have described and shown several pre-

ferred embodiments of the invention, it should be apparent that changes in structure and arrangement may be made without departing from the inventive concept which is not restricted except as indicated in the following claims.

I claim:

1. An integrally cast steel railroad crossing element comprising a top having a central portion and armlike portions extending outwardly therefrom, supporting side walls extending around the contour of the top and depending therefrom, the upper surface of said top being provided with car wheel flangeways which cross at the central portion of the element, and at least one integrally cast vertical strengthening rib depending centrally from the base of the flangeways and running longitudinally thereof, a portion of said rib being positioned directly beneath the intersection of said flangeways.

2. An integrally cast steel railroad crossing element comprising a top having a central portion and armlike portions extending outwardly therefrom, supporting side walls extending around the contour of the top and depending therefrom, the upper surface of said top being provided with car wheel flangeways which cross at the central portion of the element, and at least one integrally cast vertical strengthening rib depending centrally from the base of the flangeways and running longitudinally thereof, said rib extending vertically downwardly to the plane of the lower edges of said side walls and being disposed directly beneath the intersection of said flangeways.

3. An integrally cast steel railroad crossing element comprising a top having a central portion and armlike portions extending outwardly therefrom, supporting side walls extending around the contour of the top and depending therefrom, the upper surface of said top being provided with car wheel flangeways which cross at the central portion of the element, arcuate transverse strengthening webs connecting the side walls of the armlike portions adjacent said central portion, and at least one integrally cast vertical strengthening rib depending centrally from the base of a flangeway and running longitudinally thereof, said rib being positioned directly beneath the intersection of said flangeways and having at least one of its ends joined to a strengthening web.

4. An integrally cast steel railroad crossing element comprising a top having a central portion and armlike portions extending outwardly therefrom, supporting side walls extending around the contour of the top and depending therefrom, the upper surface of said top being provided with car wheel flangeways which cross at the central portion of the element, arcuate transverse strengthening webs connecting the side walls of the armlike portions adjacent said central portion, and at least one integrally cast vertical strengthening rib depending centrally from the base of a flangeway and running longitudinally thereof, said rib extending vertically downwardly to the plane of the lower edges of said side walls and having at least one of its ends joined to a strengthening web, said rib extending directly beneath the intersection of said flangeways.

5. An integrally cast steel railroad crossing element comprising a top having a central portion and armlike portions extending outwardly therefrom, supporting side walls extending around the contour of the top and depending therefrom, the upper surface of said top being provided with car wheel flangeways which cross at the central portion of the element, arcuate transverse strength-

ening webs connecting the side walls of the armlike portions adjacent said center portion, and an integrally cast vertical strengthening rib depending centrally from the base of a flangeway and running from one of said webs longitudinally of the flangeway to the point of crossing with another flangeway and then longitudinally of said last named flangeway and connecting with another of said webs.

10 6. An integrally cast steel railroad crossing element comprising a top having a central portion and armlike portions extending outwardly therefrom, supporting side walls extending around the contour of the top and depending therefrom, the upper surface of said top being provided with car wheel flangeways which cross at the central portion of the element, arcuate transverse strengthening webs connecting the side walls of the armlike portions adjacent said center portion, and an integrally cast vertical strengthening rib depending centrally from the base of a flangeway and running from one of said webs longitudinally of the flangeway to the point of crossing with another flangeway and then longitudinally of said last named flangeway and connecting with another of said webs, said strengthening rib extending downwardly to the plane of the lower edge of said side walls.

7. An integrally cast steel railroad crossing element comprising a top having a central portion and armlike portions extending outwardly therefrom, supporting side walls extending around the contour of the top and depending therefrom, the upper surface of said top being provided with car wheel flangeways which cross at the central portion of the element, arcuate transverse strengthening webs connecting the side walls of the armlike portions adjacent said center portion, and an integrally cast vertical strengthening rib depending centrally from the base of a flangeway and running from one of said webs longitudinally of the flangeway across the center portion of the element to another of said webs, and similar strengthening ribs extending from others of said webs longitudinally of other flangeways to points adjacent but spaced from said first mentioned strengthening rib.

8. An integrally cast steel railroad crossing element comprising a top having a central portion and armlike portions extending outwardly therefrom, supporting side walls extending around the contour of the top and depending therefrom, the upper surface of said top being provided with car wheel flangeways which cross at the central portion of the element, arcuate transverse strengthening webs connecting the side walls of the armlike portions adjacent said center portion, and an integrally cast vertical strengthening rib depending centrally from the base of a flangeway and running from one of said webs longitudinally of the flangeway across the center portion of the element to another of said webs, and similar strengthening ribs extending from others of said webs longitudinally of other flangeways to points adjacent but spaced from said first mentioned strengthening rib, said strengthening ribs extending downwardly to the plane of the lower edges of said side walls.

9. An integrally cast steel railroad crossing element comprising a top having a central portion and armlike portions extending outwardly therefrom, supporting side walls extending around the contour of the top and depending therefrom, the upper surface of said top being provided with car wheel flangeways which cross at the central

portion of the element, arcuate transverse strengthening webs connecting the side walls of the arm-like portions adjacent said center portion, and an integrally cast vertical strengthening rib depending centrally from the base of a flangeway and running from one of said webs longitudinally of the flangeway across the center portion of the element to another of said webs, and similar strengthening ribs extending from others of said strengthening webs longitudinally of other flangeways to points adjacent but spaced from said first mentioned strengthening rib, said strengthening ribs extending downwardly to the plane of the lower edges of said side walls, said strengthening webs having their upper edges spaced from the under surface of said top.
